UNITED STATES PATENT OFFICE.

FRANZ SEIDEL, OF MOGWITZ, GERMANY.

DESIGN FOR A PICTURE-FRAME.

SPECIFICATION forming part of Design No. 29,572, dated November 1, 1898.

Application filed September 14, 1898. Serial No. 690,966. Term of patent 3½ years.

To all whom it may concern:

Be it known that I, FRANZ SEIDEL, a subject of the Emperor of Germany, residing at Mogwitz, Schlesien, Germany, have invented and produced a new and original Design for Picture-Frames, of which the following is a specification, reference being had to the accompanying drawings, forming part thereof, in which—

10 Figure 1 is a view thereof in elevation, and Fig. 2 a transverse section on line 2 2 of Fig. 1.

As shown in the drawings, the leading or material feature of my design consists of a circular frame representing a life-preserved, 15 having exterior loops and transverse bands across the said frame.

The circular frame A, which is in the form of a life-preserved, has a projecting circumferential rim *a* and is ornamented by suitable

heraldic emblems, as shown. The frame is 20 provided also with exterior loops B, formed continuously one with the other and representing rope. Suitable transverse bands C extend across the circular frame at points between said loops. *d d* represent segmental 25 decorations in said frame.

Having thus described my invention, I claim as new and desire to secure by Letters Patent—

The design for a picture-frame, as herein 30 described and shown.

In testimony that I claim the foregoing as my invention I have signed my name in presence of two subscribing witnesses.

FRANZ SEIDEL.

Witnesses:

GEO. L. WHEELOCK,
M. HENRY WURTZEL.
